UNITED STATES PATENT OFFICE

2,526,822

GRINDER

Grover C. Leach, Brownwood, Tex.

Application December 6, 1946, Serial No. 714,476

7 Claims. (Cl. 51—106)

1

This invention relates to grinding machines and is an improvement over the construction shown in copending application Serial Number 626,407, filed November 2, 1945, for Grinding Machine, now Patent No. 2,479,579, dated August 23, 1949.

An object of this invention is to provide a grinding machine which will sharpen the edge of a plow disc and will form a convex bevel on the edge of the disc.

Another object of this invention is to provide a grinding machine of this kind which will sharpen the edge of a plow disc in such a manner that the edge of the disc will not be burned or unduly heated so that the temper of the disc will be retained.

A further object of this invention is to provide a grinding machine which is designed to sharpen a plurality of discs in one operation.

A further object of this invention is to provide in a machine of this kind an improved means for locking and declutching the disc shaft so that the disc can be readily mounted on and removed from the disc shaft.

A further object of this invention is to provide a grinding machine of this kind wherein the disc is oscillated relative to the grinding wheel so as to form a convex bevel on the edge of the disc, and also to speed up the grinding operation without undue heating of the disc.

A further object of this invention is to provide a grinding machine which is so constructed and arranged that the edges of warped discs can be sharpened without truing up the discs.

With the above and other objects in view, my invention consists in the arrangement, combination and details of construction disclosed in the drawings and specification, and then more particularly pointed out in the appended claims.

In the drawings,

Figure 1 is a detail side elevation of a grinding machine constructed according to an embodiment of this invention.

Figure 2 is a sectional view taken substantially on the line 2—2 of Figure 1.

Figure 3 is a horizontal sectional view taken substantially on the line 3—3 of Figure 1.

Figure 4 is a sectional view taken substantially on the line 4—4 of Figure 3.

Figure 5 is a fragmentary sectional view taken on the line 5—5 of Figure 1.

2

Figure 6 is a fragmentary sectional view taken on the line 6—6 of Figure 5.

Figure 7 is a fragmentary sectional view taken on the line 7—7 of Figure 6.

Figure 8 is a fragmentary sectional view taken on the line 8—8 of Figure 1.

Figure 9 is a fragmentary vertical section of one of the disc supporting units.

Figure 10 is an enlarged fragmentary sectional view taken substantially on the line 10—10 of Figure 1.

Figure 11 is an enlarged fragmentary sectional view taken on the line 11—11 of Figure 1.

Figure 12 is a sectional view taken on the line 12—12 of Figure 1.

Figure 13 is a fragmentary sectional view taken substantially on the line 13—13 of Figure 1.

Figure 14 is a fragmentary sectional view taken on the line 14—14 of Figure 1.

Figure 15 is a fragmentary sectional view taken on the line 15—15 of Figure 1.

Figure 16 is a fragmentary sectional view taken on the line 16—16 of Figure 10, showing the disc shaft in locked position.

Figure 17 is a fragmentary sectional view taken on the line 17—17 of Figure 16.

Figure 18 is a fragmentary sectional view showing the manner in which the convex bevel on the disc is formed.

Referring to the drawings, the numeral 20 designates generally a frame structure which is formed of opposite side members generally designated as 21, which are connected together by means of transverse connecting bars 22 and 23.

Each side member 21 is formed of an upper angle bar 24 and a pair of downwardly divergent supporting legs 25 which may be formed of angle bars. An intermediate angle bar 26 is connected at its upper end to the upper member 24 and is connected at its lower end to a base angle bar 27.

A longitudinal lower side bar 28 is connected between the supporting legs 25 and is also fixed to the intermediate supporting leg 26. The side member 21 also includes a pair of longitudinally curved combined bracing members and guide bars 29 and 30. The purpose for the guide bars 29 and 30 will be hereinafter described.

A grinder shaft 31 is journaled in bearings 32 carried by the upper frame bars 24 and the shaft 31 has mounted thereon a pair of pulleys 33 and

34. The pulley 33 is provided as an auxiliary driving means for the grinding shaft 31, whereby this shaft may be connected with an overhead power means where such power means is available. The pulley 34 has trained thereabout a belt 35 which extends downwardly and is trained about a lower pulley 36 which is fixed on a lower shaft 37. The lower shaft 37 is journaled in bearings 38 which are carried by the lower horizontal bars 28.

The grinder shaft 31 has mounted thereon a pair of abrading wheels 39 which are disposed outside of the frame 20. The shaft 31 is held against endwise movement relative to the bearings 32 by means of collars 40 fixed to the shaft 31 by set screws 41 on the outer sides of the bearings 32. Each grinding wheel or abrader 39 is held against endwise movement and against rotary movement on the shaft 31 by means of inner and outer collars 42 and 43. The inner collar 42 may be locked against rotation by means of a set screw or other fastening means 44, whereas the outer collar 43 is tightly clamped against the outer side of the grinding wheel 39 by means of a nut 45 which is threaded on the outer end of the shaft 31.

The lower shaft 37 also has fixed thereon a pulley 46 about which a driving belt 47 is trained. The belt 47 is also trained about a motor pulley 48 which is fixed on a motor shaft 49 connected to a motor or power member 50. The motor or power member 50 is disposed at one end of the frame 20, as shown more clearly in Figure 3. A guard is disposed about each grinding wheel 39, being generally designated 51. Each guard 51 is formed of inner and outer walls 52 and 53 (Fig. 5) and an arcuate bottom wall 54. The side walls of the guard are formed with a cutout 55 so that the guard may be raised to the desired position and at the same time expose the desired amount of grinding wheel surface.

The guard 51 has fixed to the lower end thereof a U-shaped clamping member 56 which extends vertically from the bottom wall 54 and is formed with oppositely extending flanges 57. The flanges 57 extend above the U-shaped member 56 and are adapted to engage against the inner side of the inner wall 52, as shown at 58, and are secured thereto by fastening members 59. The intermediate leg or frame member 26 has fixed thereto an angle member 60 which has one side thereof extending outwardly and formed with an elongated vertically disposed slot 61 through which a bolt or fastener member 62 engages.

The bolt or fastening member 62 extends through the legs of the clamping member 56 so that the guard may be vertically adjusted and locked in its adjusted position with respect to its associated grinding wheel.

The frame 20 has mounted on the outer sides thereof a plurality of disc supporting members generally designated as 63, 64, 65, and 66. These disc supporting and rotating means are identical as to the details of their construction and the detailed description of one of these disc supporting members will apply equally as well to the other members.

The disc supporting member 63 comprises a pair of parallel bars 67 and 68 (Fig. 2) which are connected together at the lower ends by a bushing 69. The bushing 69 is rockably mounted on a horizontal shaft 70 which is journaled in bearings 71 carried by the lower horizontal bars 28. The bushing 69 is loose on the outer end of the shaft 70 so that this shaft can have rotation independ-

ent of the movement of rocking of the arms 67 and 68, and the bushing 69. Arm 67 has fixed thereto by fastening members 72, an upwardly extending arm or lever 73 formed adjacent the upper end portion thereof with an outwardly offset portion 74. Arm or lever 68 has fixed thereto by fastening members 75 an upwardly extending arm or lever 76.

A gear housing 77 is disposed between the upper 10 ends of the lever members 74 and 76 and is adapted to have rocking movement between the lever arms or members 74 and 76 as will be hereinafter described. The housing 77, shown more 15 clearly in Figures 10 and 11, has fixed to the outer side wall 78 thereof a trunnion or stub shaft 79. This trunnion or stub shaft 79 rockably engages through an opening 80 formed in the arm or lever extension 74. A second stub shaft 81 is journaled through a bushing 82 which is fixed to the lever member 76 and extends through the inner side wall 83 of the housing 77.

A beveled gear 84 is fixed on the outer end of the stub shaft 81. The inner wall 83 may be formed with a bearing boss 85 on the outer side thereof 25 and a second bearing boss 86, formed with a flange 87 is secured by fastening members 88 to the inner side of the inner wall 83. The shaft 81 rotatably engages through the bearing bosses 85 and 86. The shaft 81 has fixed thereto a pulley 89 about 30 which a belt 90 is trained. The belt 90 is also trained about a lower pulley 91 which is fixed on the shaft 70.

The belt 90 is maintained taut by means of an idler pulley 92 which is carried by a crank 93 and the crank 93 is journaled through a pair of lugs 94 which are fixed to the lever members 73 and 76. The crank 93 includes a crank handle 95 which may be locked in inoperative position by engagement with a notched keeper 96 which is fixed to and extends from the lever or arm 67.

A disc rotating shaft 97 is journaled through upper and lower bearings 98 and 99, carried by the upper and lower walls 100 and 101 of the housing 77. The shaft 97 is formed with a longitudinally extending keyway 102 and a beveled gear 103 is mounted on the shaft 97, having a boss 104 which includes a key 105 slidably engaging in the keyway 102. In this manner the gear 103 may be moved lengthwise of the shaft 97.

Gear 103 meshes with gear 84 and gear 103 may be moved endwise on the shaft 97 by means of a sleeve 105 loosely engaging about the shaft 97 below the gear 103. The sleeve 105 engages between a shifting fork 106 which is rockably mounted on a pair of ears 107 which are fixed to the rear wall 108 of the housing 77. The arms of the fork 106 are rockably secured to the sleeve 105 by means of pivot members 109 which are fixed to the sleeve 105. The fork 106 includes an outwardly extending arm 110 which is formed with a beveled upper edge 111. The arm 110 also includes, as shown in Figure 1, a substantially L-shaped lever 112 by means of which the fork 106 may be raised or lowered. When the fork 106 is in its raised position to thereby disengage gear 103 from gear 84, arm 110 will engage between a pair of teeth on the gear 103, as shown in Figures 16 and 17, so as to thereby lock gear 103 in its disengaged position from rotation and also lock disc shaft 97 against rotation. This locking of shaft 97 is provided in order that a disc may be readily mounted on or removed from the upper end of shaft 97.

The disc shaft 97 extends above the bearing 78 and has mounted thereon adjacent the upper

end thereof a cup-shaped disc support 113 formed with a peripheral flange 114. A plow disc 115 is adapted to engage the cup-shaped support 113 and preferably a cushioning member 116 is interposed between the convex lower side of the plow disc 115 and the flange 114. The disc 115 is tightly clamped on the support 113 by means of a nut 117 carried by a hand wheel 118 and the disc 115 is adapted to be centered with respect to the shaft 97 by means of a cone-shaped centering member 119 which will engage in the center hole of the disc 115.

In order to prevent undue noise or vibration of the peripheral edge of the disc when the latter is in engagement with the grinding wheel 39, I have provided a dished plate 120 which has mounted on the peripheral edge thereof cushioning member 121. The dished member 120 is adapted to be tightly engaged within the concave side of the plow disc 115 by means of a nut 122 which engages a centering cone 123 adapted to engage in the center hole of the dished member 120. The upper end of the bearing 98 is protected against the entrance of any abrading material by means of a cone-shaped guard or shield 124 disposed loosely about the shaft 97, as shown more clearly in Figure 9.

The L-shaped lever 125 is adapted to be held in either clutching or declutching position by means of a notched keeper 124 which is fixed to the top wall 108 of the housing 77 and extends downwardly and outwardly therefrom. The shaft 97 is adapted to be adjusted in the desired angular relation with respect to the supporting arms therefor when the plow disc is in inoperative position, by means of an elongated lever 125 which at its inner end is fixed on the stub shaft 79.

The lever or arm 125 is longitudinally curved, as shown in Figure 1, and has extending upwardly from an intermediate point a pair of bars or plates 126 which engage on the opposite sides of an elongated bar 127 pivotally mounted, as at 128, on the upper end of the lever extension 74.

A clamping bolt 129 extends through the ears or plates 126 and a nut 130 is threaded on the bolt 129 so that the shaft 97 may be locked in the desired upright position for mounting or removing a plow disc from the shaft. When the plow disc is being ground nut 130 is loosened so that the peripheral edge of the plow disc will loosely engage the grinding wheel 39. A spring 131 is connected at its upper end to an ear 132 carried by the housing 77 and is connected at its lower end to a hook-shaped tensioning bolt 133 which engages through an arm 134 fixed to the bushing 69. In this manner the shaft 97 will be spring-pressed to hold the edge of the plow disc against the grinding wheel, but if the plow disc should be warped the disc may have undulating motion in order that the entire warped portions of the disc at the peripheral edge thereof will be sharpened in a proper manner.

In order to provide for the formation of a convex bevel at the peripheral edges of the disc, which convex bevel is designated in Figure 13 by the numeral 135, I have provided an oscillating means for oscillating or rocking the disc supporting unit as the disc shaft 97 is being rotated. This oscillation is accomplished by means of an elongated link or pitman 136 which is connected at its inner end to a crank pin 137 carried by a shaft 138. The shaft 138 is journaled through bearings 139 which are carried by a pair of upwardly extending bearing supporting plates 140

fixed to the lower horizontal bars 28. The shaft 138 has fixed thereon a pulley 141 about which a belt 142 is trained, and the belt 142 is trained about a small driving pulley 143 mounted on a shaft 144. The shaft 144 has a large gear 145 fixed thereon which meshes with a small gear 146 carried by a shaft 147. The shaft 147 is journaled through a pair of bearings 148 carried by the lower horizontal bars 28.

Shaft 147 has fixed thereon a pulley 149 about which a belt 150 is trained, and the belt 150 is also trained about a small driving pulley 151 mounted on the shaft 37.

In order to maintain the belt 142 taut, I have provided an idler pulley 152 which is rotatably carried by a rock lever 153. The lever 153 is spring-pressed upwardly to belt tightening position by means of a spring 154. The outer end of the link or pitman 136 is adapted to be adjustably clamped to a rock lever 155 by means of a pair of clamping bars 156. The clamping bars 156 (Fig. 15) are pivotally mounted on a bolt 157 extending through the outer end of the pitman 136, and the outer ends of the bars 156 are adapted to be clamped to the lever 155 by means of a clamping bolt 158 having a nut 159 threaded thereon.

Rock lever 155 is pivotally mounted on a pivot member 160 carried by an ear 161 extending from the adjacent frame supporting leg 25 and the upper end of lever 155 has rockably mounted thereon a stub shaft 162 engaging through a bushing 163 which is fixed on the lever 155. The shaft 162 includes a bushing 164 through which a screw shaft 165 rotatably engages and the shaft 165 is threaded through a nut 166 rockably carried by a stub shaft 167. The stub shaft 167 loosely engages through a bushing 168 which is carried by the upper end and extends inwardly from the lever 76. The shaft 165 has fixed thereon at its outer end a hand wheel 169 and the shaft 165 is protected against falling abrading material by means of a shield or guard 170. The shield or guard 170 may be of substantially L-shape in transverse section and the inner end of the guard 170 has a bearing block 171 fixed thereto within which the inner end of the screw shaft 165 rotatably engages. Adjustment of the screw shaft 165 will adjust the angular position of the levers comprising the unit 63 and which include the levers 67, 68, 73, 74 and 76.

The crank 93 which carries the belt tensioning idler 92 is constantly urged to operative position by means of a spring 172 which is secured at one end to an arm 173 carried by the inner lever 76 and is secured at the other end to an arm 174 extending angularly from the upper end of the crank member 93. The associated member 64 of the pair of disc supporting units 63 and 64 is oscillated in unison with the oscillation of unit 63 by means of a short pitman 175 which is connected at its inner end to the crank pin 137. In order to hold the levers 73 and 76 against lateral movement during the oscillation thereof, the upper end of lever 76 has an L-shaped flange 176 secured thereto which loosely engages on the inner side of guide member 30. The inner side of the lever 76 is adapted to engage the outer side of guide member 30 so that the unit is firmly held at its upper free end against lateral movement, particularly during the oscillation thereof.

In the use and operation of this machine, the plow disc 115 is clamped by means of the clamping nut 117 on the upper end of shaft 97. At

this time shaft 97 may be disposed in substantially vertical position, as shown in Figure 1, and clutch lever 112 will be disposed in the raised position shown in Figure 16, when the gear 103 is raised to a disengaged position with respect to gear 84. Locking member 111 will be engaged between a pair of teeth on gear 103 so that shaft 97 will be firmly locked against rotation. When lever 112 is latched in its gear disengaging position, the remaining units of this machine may be operated due to the fact that gear 84 may continue to operate. When clutch lever 112 is lowered, gear 103 is moved downwardly by means of a U-shaped gear shift member 177 which is fixed to the upper end of sleeve 105.

After the plow disc has been clamped to the upper end of shaft 97, lever 125 is released from lever 127 and screw shaft 165 is turned so as to swing the levers 67, 68, 73 and 76 inwardly on the desired angle so that the peripheral edge of the disc will engage the grinding wheel 39. The oscillating link 136 which rocks the levers 67, 68, 73 and 76 is adjusted by adjusting the clamping bars 156 relative to the lever 155 so that the desired length of bevel will be ground on the edge of the disc.

When lever 125 is released from bar 127, spring 131 will swing housing 77 downwardly and inwardly to yieldably hold the edge of the disc against the abrading wheel. Shaft 31, upon rotation thereof with the driving connections to the power member, will rotate the grinding wheels and as these wheels rotate shaft 97 will be rotated so as to rotate the peripheral edge of the plow disc 115 across the cutting face of the grinding wheel 39. As the grinding operation is taking place, pulley 141 will rotate shaft 138 so as to reciprocate pitman 136, and the reciprocation of this pitman will rock lever 155 and the rocking of lever 155 will effect rocking of levers 67, 68, 73 and 76. Inasmuch as the disc shaft is rockably mounted on the upper ends of levers 74 and 76, being constantly urged downwardly and inwardly by spring 131, the plow disc will be given an upward and inward movement relative to the abrading surface of wheel 39 in order that the bevel formed on the edge of the disc will be a convex bevel as shown at 135 in Figure 18.

With a machine as hereinbefore described, a pair of plow discs may be sharpened at one time by the same grinding wheel and it will, of course, be understood that the pairs of disc supporting members may be duplicated as may be desired so that any number of units may be mounted in the same frame. In the drawings there are disclosed two units, each comprising a pair of plow disc supporting members, so that, as herein disclosed, four plow discs may be simultaneously sharpened by this machine. By providing a machine as hereinbefore described, and particularly by providing for the rocking of the disc as it is being sharpened and rotated, the edge of the disc will not become unduly heated so that the temper of the disc will not become injured during the sharpening thereof. Due to the rotation of the plow disc as it is being sharpened, the edge will be quickly sharpened and in the event the disc is warped at any point, the grinding wheel will not have the effect of truing up the disc due to the rockable mounting of the disc shaft on the oscillating lever construction.

I do not mean to confine myself to the exact details of construction herein disclosed, but claim all variations falling within the purview of the appended claims.

What I claim is:

1. A grinding machine comprising a frame, an abrading wheel rotatably carried by said frame, a lever structure rockably carried by said frame, an article supporting shaft, means rotatably and swingably mounting said shaft on said lever structure, spring means constantly urging said means to rock toward said wheel, and means rotating said shaft and means operatively connected with said shaft rotating means for oscillating said lever structure.

2. A grinding machine comprising a frame, an abrading wheel rotatably carried by said frame, a lever structure rockably carried by said frame, an article supporting shaft, means rotatably and swingably mounting said shaft on said lever structure, spring means constantly urging said means to rock toward said wheel, means rotating said shaft, and means operably connected with said rotating means for oscillating said lever structure.

3. A grinding machine comprising a frame, an abrading wheel rotatably carried by said frame, a lever structure rockably carried by said frame, an article supporting shaft, means carried by said lever structure rotating said shaft, means swingably mounting said shaft on said lever structure, means for rocking said lever structure simultaneous with rotation of said shaft rotating means, means securing an article on said shaft, and spring means biasing said shaft for engaging the article with said abrading wheel.

4. A grinding machine comprising a frame, an abrading wheel rotatably carried by said frame, a lever structure rockably carried by said frame, an article supporting shaft, means carried by said lever structure rotating said shaft, means swingably mounting said shaft on said lever structure, means for rocking said lever structure simultaneous with rotation of said shaft rotating means, means securing an article on said shaft, spring means biasing said shaft for engaging the article with said abrading wheel, and means locking said shaft against swing on said lever structure.

5. A grinding machine comprising a frame, an abrading wheel rotatably carried by said frame, a lever structure rockably carried at the lower end thereof by said frame, an article supporting shaft, means rotatably and swingably mounting said shaft on the upper portion of said lever structure, spring means constantly urging said first named means to rock toward said wheel, and means operatively connected to said shaft mounting means for rotating said shaft and simultaneously oscillating said lever structure, said latter means including means for selectively disconnecting said shaft from said rotating means and locking said shaft against rotation.

6. A grinding machine comprising a frame, an abrading wheel rotatably carried by said frame, a lever structure rockably carried by said frame, an article supporting shaft, means rotatably and swingably mounting said shaft on said lever structure, spring means constantly urging said means to rock toward said wheel, power actuated means connected with said rotating means and said lever structure for oscillating said lever structure, and means for varying the oscillation of said lever structure.

7. A grinding machine comprising a frame, an abrading wheel rotatably carried by said frame, a lever structure rockably carried by said frame, an article supporting shaft, means rotatably and swingably mounting said shaft on said lever struc-

ture, spring means constantly urging said means to rock toward said wheel, means carried by said frame and said lever structure rotating said shaft and simultaneously oscillating said lever structure, and means securing an article on said shaft in a manner whereby the article will be held against vibration.

GROVER C. LEACH.
